UNITED STATES PATENT OFFICE.

ROBERT H. FOWLER, THOMAS BENSTEAD, AND ALFRED PEPPER, OF
LEEDS, ENGLAND.

MECHANICALLY-WORKED PLOW.

SPECIFICATION forming part of Letters Patent No. 764,445, dated July 5, 1904.

Application filed June 15, 1903. Serial No. 161,594. (No model.)

To all whom it may concern:

Be it known that we, ROBERT HENRY FOWLER, engineer, THOMAS BENSTEAD, draftsman, and ALFRED PEPPER, engineer, all of Steam 5 Plow Works, Leeds, in the county of York, England, have invented certain new and useful Improvements in Mechanically - Worked Plows, of which the following is a specification, for which I have applied for a patent in 10 Great Britain, dated January 30, 1903, No. 2,303.

This invention relates to improvements in the construction of standards adapted primarily to be used on mechanically-worked plows 15 to secure strength, side stiffness, and lightness, and also provides means for the ready and accurate adjustment of the shares on such plows to suit the requirements of working different kinds of soil.

20 In the accompanying drawings, Figure 1 is an elevation showing the improved construction of standard which forms one part of the present invention; and Fig. 2 is a part section on line 2 2 of Fig. 1, showing the method of 25 attaching the standard to the main frame of the plow.

Referring to Figs. 1 and 2, the plow-standard consists of a plate *a*, preferably corrugated or flanged, or both, or otherwise reinforced by strengthening - ribs, except at its 30 lower end, where the surface is left flat for the reception of the frog *b*, which has a corresponding flat face at its upper part and to which the share and moldboard are attached 35 in the usual manner. The body is fixed to the main frame *c*, which is preferably of channel section, by stirrup-bolts *d* or other suitable means and to the frog *b* by a pivot-bolt

e and one or more clamping-bolts *f*, which latter pass through segmental slots *f'* in the 40 frog. The adjustment is effected by a screwed bolt *g*, pivoted on a pin or bolt *g'*, fixed to the body and passing through an eye *g*² in the skife, to which it is fixed by nuts *g*³ on either side of the eye. 45

Having thus described the nature of this invention and the best means we know of carrying the same into practical effect, we claim—

The combination of a plow-standard, the upper part of which is corrugated and the lower 50 portion of which is flattened, a frog correspondingly flattened to fit against the flat portion of the standard, said frog having a projection at its rear, a bolt having an eye at its upper end, the threaded portion of the bolt 55 extending through a perforation in said projection, nuts upon the threaded portion of the bolt at opposite sides of the projection, a pin passing through said eye, carried by the standard, a pivot uniting the standard and frog, 60 said two last-mentioned parts having registering perforations to receive said pivot, and clamping-bolts passing through openings in the standard and frog respectively, one opening in each case being elongated, and the re- 65 spective openings and perforations being triangularly arranged.

In witness whereof we have hereunto set our hands in presence of two subscribing witnesses.

R. H. FOWLER.
THOMAS BENSTEAD.
ALFRED PEPPER.
